UNDERDRAIN UNIT FOR WATER FILTRATION SYSTEM

James Raymond Sturgill, Charlotte, N.C., assignor
to Hi-Ran Ltd.

Filed Mar. 3, 1975, Ser. No. 554,396

Term of patent 14 years

Int. Cl. D23—01

U.S. Cl. D23—4

FIG. 1 is a perspective view of an underdrain unit for water filtration system showing my new design, portions broken away to indicate indeterminate length;

FIG. 2 is an end elevational view looking from the right of FIG. 1; and

FIG. 3 is an end elevational view looking from the left of FIG. 1.

The side opposite that shown in FIG. 1 is the same as the side shown.

I claim:

The ornamental design for an underdrain unit for water filtration system, substantially as shown and described.
